CLAIM

The ornamental design for a display screen with graphical user interface, as shown and described.

DESCRIPTION

The sole FIGURE is a front view of the display screen with graphical user interface.

The outermost long-dashed broken lines illustrate an electronic device, which constitutes the environment of the design and forms no part of the claim. The intermediate-length dashed broken-lines illustrate a display screen and the boundary of the design and form no part of the claim. The remaining short-dashed broken lines illustrate portions of the graphical user interface that form no part of the claimed design.

The shaded regions depict a contrast in appearance.
